SHOE CONSTRUCTION

Clarence H. Raut, Chicago, Ill.

Application October 28, 1932. Serial No. 639,937

4 Claims. (Cl. 36—71)

The invention relates generally to a shoe construction and more particularly to the construction of the rear or heel portion of the shoe.

In this portion of a shoe, especially in men's shoes, a counter preferably made of relatively stiff leather is used between the soft outer leather, constituting a part of the upper, and the lining. The purpose of the counter is to stiffen this portion of the shoe to prevent wrinkling and to hold the shoe on the foot. The counter usually has a portion turned laterally inward which may be skived to blend in with the adjacent parts of the shoe, said portion obviously forming a rounded bend with the counter proper.

In a higher grade shoe, the counter is shaped so that the lower portion of the counter proper is straight forming substantially a continuation of the side or edge surface of the sole and heel lifts. In such a shoe, the quality of the leather in the counter is such that this relationship exists to a great extent during the life of the shoe, thus maintaining the original neat appearance of this portion of the shoe.

In cheaper shoes, the counter, while it may provide the proper appearance when the shoe is new, is made of such leather or other material that this relationship with the sole and heel lifts will not be maintained. The counter weakens and this portion of the shoe bulges outwardly beyond the side surface of the heel lifts, producing a sloppy appearance and indicating the cheapness of the shoe.

The general object of the invention is to provide a construction in which the counter is stiffened, thus maintaining the proper appearance throughout the life of the shoe and to a greater extent than even in the better grade of shoes.

Another object is to provide a construction attaining the foregoing object, but which is inexpensive to manufacture.

A further object is to provide a construction of this character which maintains the proper appearance of the outside of the shoe and at the same time provides the proper support for and properly fits the heel of the foot.

Other objects and advantages will become apparent from the following description taken in connection with the accompanying drawing, in which:

Figure 1 is a rear view, partially in section, of a shoe embodying the features of the invention.

Fig. 2 is a fragmentary side view partially in section.

As shown in the drawing, the present embodiment of the invention comprises a sole 10 under

the heel of which are attached a suitable number of heel lifts 11. The side edges of the heel lifts are flush with the side edge of the sole to form a substantially vertical surface.

Attached to the sole 10 is an upper 12 usually made of rather soft pliable leather. A portion of the upper is turned inwardly, as shown at 13, and is attached to the sole.

To stiffen the portion of the upper which extends around the heel of the foot to prevent it from wrinkling during wear and to make the shoe fit the heel of the foot, a counter is provided comprising a stiffening portion 14 and an attaching portion 15 turned laterally inward as at 16 and secured in any suitable manner to the sole, the upper surface of this portion of the sole and the attaching portion 15 constituting the heel seat. The lower part of the stiffening portion 14 is shaped in a straight line so that the upper constitutes substantially a continuation of the surface formed by the side edges of the sole and heel lifts, while the turn of the counter fits the heel of the foot. Within the shoe is an insole 19 overlying the sole and the portion 15 of the counter, which is curved upwardly at its sides because of the portion 15, and thus fits the heel of the foot.

As mentioned above, in higher grade shoes, the counter is made of such quality of leather that this relationship between the upper and said vertical surface is substantially maintained during the life of the shoe. This relationship gives a neat appearance to the shoe, and is desired for that reason.

In the cheaper shoes, the cost of using leather for the counter which has the quality of maintaining its stiffness is excessive, so that cheaper leathers or other materials are used. A counter made of such cheaper material, while it may provide the proper appearance when the shoe is new, loses its stiffness in wear, permitting an unsightly bulge above the heel seat and destroying a proper fit of the shoe on the foot.

To stiffen the counter and overcome any tendency for it to bulge, the present invention contemplates the provision of reinforcing means therefor. As shown herein, the reinforcing means comprises a strip 17 of relatively stiff leather extending around the counter. Preferably, the strip 17 is positioned along the lower edge of the stiffening portion 14 of the counter at the turn 16 thereof and inside of the upper 12. Thus, the strip reinforces the counter and stiffens it where it has the greatest tendency to bulge.

The strip 17 has the further function of shaping the adjacent portion of the upper 12. To this end, the lower raw edge of the strip 17, as shown at 18, is flush with or slightly below the 5 under surface of the attaching portion 15 of the counter, the strip being skived or sanded to form a continuation of the side surface of the counter. Thus, the strip fills in the space adjacent 10 the turn 16 of the counter and holds the upper in the desired position relative to the vertical side edges of the sole and heel lifts and makes a tight heel seat.

The strip 17 may be secured in place by cementing it to the counter and thus is rigid 15 therewith.

From the above description, it will be apparent 20 that I have provided a shoe construction in which the counter is stiffened in a manner which will maintain the proper appearance of this part of the shoe throughout the life thereof, and which maintains such appearance to a greater extent than has heretofore been accomplished by the construction employed in higher grade shoes. It will also be apparent that the construction herein described is inexpensive to 25 manufacture, and provides a proper fit of the shoe to the heel of the foot and a proper external appearance in this part of the shoe.

I claim as my invention:

30 1. In a shoe, the combination of a sole, a counter of relatively stiff material having its lower edge turned inwardly and attached to the upper surface of the sole and leaving a ledge around the sole extending outwardly beyond the 35 inturned portion of the counter, an upper of relatively soft material covering the outer face of the counter and having its lower edge secured between the sole and the inturned portion of the counter, and a reinforcing strip positioned between the upper and the counter adjacent the 40 inturned portion of the latter with its upper edge skived to blend into the counter and its lower edge holding the upper tightly against the ledge, said lower edge of the strip being of sufficient thickness to shape the upper so that it 45 forms a continuous unbroken surface with the side edge of the sole.

2. In a shoe, the combination of a flat sole, a counter turned inwardly over the sole to form a rounded inner surface shaped to fit the heel of the foot, the inturned portion of the counter being secured to the sole, an upper covering the outer surface of the counter with its lower edge secured between the counter and the sole, and a shaping strip between the upper and the turn in the counter holding the upper tightly against the top face of the sole at the edge thereof so that the upper and the side edge of the sole form a continuous unbroken surface.

3. The combination with a shoe comprising a flat sole, a counter of stiff material turned inwardly over the sole and secured thereto, said turn being rounded because of the stiffness of the material, and an upper covering the outer face of the counter and turned inwardly and secured between the inturned portion of the counter and the sole, of means for shaping the upper adjacent the sole comprising a shaping strip extending along the turn of the counter and resting edgewise against the inturned portion of the upper, the lower outer corner of said strip being relatively sharp to hold the upper tightly against the sole.

4. In a shoe, the combination of a sole, a counter of relatively stiff material having its lower edge turned inwardly and attached to the upper surface of the sole and leaving a ledge around the sole extending outwardly beyond the inturned portion of the counter, an upper of relatively soft material covering the outer face of the counter and having its lower edge secured between the sole and the inturned portion of the counter, and a shaping element located in the space between the outer surface of the inturned portion of the counter, the ledge on the sole and the upper, and bearing down on the upper to hold the upper against the ledge for maintaining the upwardly extending portion of the upper immediately adjacent the sole substantially flat and substantially flush with the side edge of the sole.
